UNITED STATES PATENT OFFICE

JACOB H. SISLER, OF NIAGARA FALLS, NEW YORK

OIL BURNER

Application filed April 19, 1928. Serial No. 271,207.

The present invention relates to improvements in oil burners and has for its principal object to provide a burner structure for association with a boiler for heating water, the steam generated in the boiler being partially mixed with the supply of oil and air, whereby to obtain proper atomization of the fuel.

A further object is to provide an oil burner of the above mentioned character which includes a means for regulating the flow of oil to the burner head as well as regulating the supply of steam, the burner head terminating at a point above the fire box of the boiler and extending into the fire box is a burner flue for directing the flame from the boiler head into the fire box and onto a flame spreader.

A still further object is to provide an oil burner of the above mentioned character, which will, at all times be positive and efficient in its operation, the same being further simple in construction, inexpensive, strong and durable, and further well adapted to the purpose for which it is designed.

Other objects of the invention will become apparent as the nature of the invention proceeds and when taken in connection with the accompanying drawings.

In the accompanying drawings, forming a part of this application and in which like numerals designate like parts throughout the several views:

Figure 1 is a side elevation of the burner embodying my invention showing the same associated with a boiler structure.

Figure 2 is a top plan view of the boiler, showing the smoke outlet pipe extending therefrom, and also disclosing the arrangement of the various pipes that extend downwardly into the top of the boiler.

Figure 3 is a horizontal section, taken approximately on the line 3-3 of Figure 1, looking in the direction of the arrows.

Figure 4 is a vertical sectional view, through the burner head.

Figure 5 is a cross sectional view, taken approximately on the line 5-5 of Figure 1.

Figure 6 is a top plan view of the flame spreader,

Figure 7 is a sectional view, taken approximately on the line 7-7 of Figure 6, and

Figure 8 is a vertical sectional view taken approximately on the line 8-8 of Figure 1.

In the drawings, wherein for the purpose of illustration is shown the preferred embodiment of my invention the numeral 1 designates generally a boiler structure, the same being provided with a removable top 2, and provides a closure for the fire box 3, the water jacket 4 surrounding the fire box. A cold water inlet pipe 5 extends into the jacket 4 and a hot water outlet 6 extends from the water jacket through the side of the boiler, and has communication with a receiving unit 7 from which extends a heat pipe 8.

Additional heat pipes may also extend from this unit. These heat pipes extend into the various rooms of a building for heating the same, in the manner well known in the art.

A plurality of steam generator units, designated generally by the numeral 9 are arranged vertically in the fire box 3 of the boiler 1, in annular spaced relation with respect to each other, as more clearly illustrated in Figure 3 of the drawings. Each steam generator unit, includes a cylindrical casing 10, that is open at its respective ends, closure heads 11 being provided for the ends of the casing. Each of the steam generator units is suspended from the removable top 2, and the lower ends of the steam generator units are spaced with respect to the bottom of the fire box. A water delivery pipe 12 extends downwardly into each casing, and one of the steam generator units is supplied with water by having its pipe communicating with the water tank 13, supported above the boiler and the supply pipe for this particular steam generator unit is designated by the numeral 14, the same including a plurality of sections that are connected together in communicating relation by a suitable fitting, shown at 15. The water will be supplied to this particular steam generating unit by gravity, due to the height at which the tank 13 is arranged.

The other steam generator units have 100

their water delivery pipes 12 extending downwardly from the high pressure water supply pipe 16, as shown in Figure 1 and the pipe 14 may also be connected in communicating relation with the high pressure water supply pipe 16, through the medium of the pipe 17 and suitable fittings 18. A valve 19 is arranged in each of the water delivery pipes for controlling the supply of water to the steam generator units.

A steam receiving jacket 7' has communication with one of the steam generator units 9 through the medium of the pipe 6', and a steam outlet pipe 8' extends upwardly from the jacket 7'.

A burner flue 20 is supported at its upper end in the center portion of the top 2 and the steam generator units 9 are disposed around this burner flue. This burner flue 20 extends downwardly into the fire box 3 and terminates in spaced relation with respect to the central portion of a flame spreader unit 21, that rests in the bottom of the fire box.

The flame spreader consists of a circular disc of suitable thickness that is formed on its upper and bottom faces with the corrugations 22, that extend radially from a flat central portion 23, as more clearly disclosed in Figures 6 and 7 of the drawings. A lug or baffle 24 is formed on the upper face of this disc like member.

The oil burner further includes the provision of the burner head that consists of a cylindrical shell 25, open at its respective ends.

A closure plug 26 is threaded in the upper end of the shell 25 while detachably secured in the open lower end of the shell for disposition directly over the open upper end of the burner flue 20 is the nozzle or burner tip 27.

A nipple 28 is formed on one side shell for communication therewith and the bore of the nipple is slightly less in diameter than the enlarged bore of the shell. The outer end of the nipple 28 is internally threaded for receiving the threaded disc like closure 29 and this closure is formed with a central threaded opening for receiving the outlet end of an oil delivery pipe 30 that has communication with an oil supply tank 31, also arranged above the burner head and to one side thereof, whereby the oil will be fed to the burner head by gravity. A manually actuated valve 32 is arranged in the delivery pipe 30 for regulating the flow of the oil from the tank 31 to the burner head, and a check valve 33 is also arranged in the horizontal portion of the delivery pipe, to preclude any possibility of the flames reaching the oil supply tank.

The cylindrical shell 25 of the burner head is formed with suitable air inlet openings 34, in the intermediate portion thereof, and extending downwardly through the closure plug 26 into the shell is a steam delivery

tube or relatively small pipe 35, the lower end of this steam pipe extending into the nozzle or burner tip 27, in the manner as clearly shown in Figure 4 of the drawings.

Steam is supplied to the pipe 35 through the supply pipe 36 that extends upwardly from a steam chamber 37 that is associated with one of the steam generating units 9 for disposition above the top 2 and this particular steam generator unit has the water supplied thereto from the tank 13 through the pipe 14 in the manner heretofore explained. A branch pipe 38 affords communication between the intermediate portion of the vertical supply pipe 36 and the upper portion of the delivery pipe 35, and the usual fittings or couplings are associated with the pipes to assemble the same together in communicating relation.

The safety check valve unit, designated generally by the numeral 39 is associated with the upper exhaust end of the vertical pipe 36. A steam pressure gage 40 is arranged on the upper end of the delivery pipe 37. A steam gage 41 is associated with the heat pipe 8' and a thermometer 42 is associated with the heat pipe 8, as clearly indicated in Figure 1.

The invention further comprehends the provision of a smoke consumer, and the same comprises a rearwardly extending upwardly inclined pipe 43 that is arranged in the fire box 3, the forward lower end of this pipe communicating with the lower end portion of the burner flue 20 by means of the fitting shown at 44 in Figure 3. A smoke flue 45 extends upwardly from the rear portion of the boiler and has communication with the upper end of the pipe 43. A smoke passage 48 is formed in the side of the fire box 3 adjacent its top for affording communication between the fire box and the smoke chamber 49 that extends around the water jacket.

A damper 46 is arranged in the smoke flue 45 as indicated in Figure 2. The top 2 for the boiler 1 is formed with an opening whereby access to the interior of the fire box may be had, and this opening is normally closed by means of the hinged door 47.

In operation, water is supplied to the several units 9, and oil is supplied to the burner head through the delivery pipe 30. The oil will be mixed with a supply of steam and air and enters the shell 25 of the burner head, so that the oil will be properly atomized before it is ignited and the vaporized fuel will project downwardly through the burner flue 20 and will be directed against the corrugated upper face of the flame spreader 21 that is arranged in the bottom of the fire box, so that the flame will be directed radially to heat the steam generator units 9.

Any appropriate means may be provided for either automatic or manual actuation to control the supply of the oil and steam, such as is well known in the art.

A suction will be created in the fitting 44 to draw the smoke from the chamber 49 through the pipe 43 so that the smoke will be consumed by the flame in the fire box when the damper is not fully opened.

5 The flame spreader will furthermore direct the flame against the inner wall of the fire box to heat the water jacket 4, whereby said boiler may be utilized as a heating plant for 10 heating the rooms of a dwelling or the like, through the provision of the heat pipes 8.

It will thus be seen from the foregoing description that I have provided an oil burner for use in conjunction with a boiler which 15 will, at all times, be positive and efficient in its operation and by admixing steam and air with the fuel, the operation of the burner will be very inexpensive.

It will also be observed that a relatively 20 large amount of oil is delivered to the burner tip or nozzle, whereas a small amount of steam is supplied to the burner head, whereby to obtain a relatively strong flame.

The parts comprising the oil burner are so 25 arranged as to render the same readily and easily accessible for adjustment or assembly.

The boiler is for hot water or steam, and the 30 steam generators 9 inside the fire box can be used for hot water or steam, whereby two systems can be heated at the same time, also one generator unit may be used for a hot water tank.

Having thus described my invention, what 35 I claim as new is:

1. In combination, a furnace provided with an open top fire box, a cover therefor, a burner flue open at its respective ends and extending downwardly from the central portion of 40 the cover into the central portion of the fire box, a series of steam generator units arranged concentrically about the burner flue in spaced relation, said units being suspended from the cover and being spaced with respect to the bottom of the fire box, a burner head 45 positioned directly above the upper end of the burner flue, whereby the flame of the burner head will be projected downwardly through the burner flue, and a flame spreader arranged beneath the lower end of the burner flue and the steam generator units for effecting the 50 heating of said units.

2. In combination, a furnace provided with an open top fire box, a cover therefor, a burner 55 flue open at its respective ends and extending downwardly from the central portion of the cover into the central portion of the fire box, a series of steam generator units arranged concentrically about the burner flue in spaced relation, said units being suspended from the 60 cover and being spaced with respect to the bottom of the fire box, a burner head positioned directly above the upper end of the burner flue, whereby the flame of the burner head will be projected downwardly through 65

the burner flue, and a flame spreader arranged beneath the lower end of the burner flue and steam generator units for effecting the heating of said units, means for supplying steam generated in one of the units to the burner head, as and for the purpose described.

3. In combination, a furnace provided with an open top fire box, a cover therefor, a burner flue open at its respective ends and extending downwardly from the central portion of 70 the fire box, a burner head positioned directly above the burner flue whereby the vapor of the burner head will be projected downwardly through the burner flue, a flame spreader arranged beneath the lower end of the burner flue, and a smoke consumer unit connected with the lower end of the burner flue comprising an upwardly extending pipe communicating at its lower end with the lower end of the burner flue, the upper end of the 75 pipe extending exteriorly of the furnace for communication with a smoke flue.

In testimony whereof I affix my signature.
JACOB H. SISLER.
